UNITED STATES PATENT OFFICE.

HARRY E. ALMENDINGER, OF ROCKY RIDGE, OHIO.

INCUBATOR.

Application filed August 10, 1923. Serial No. 356,642.

This invention relates to multiple chamber and multiple tray incubators.

This invention has utility when incorporated as a sectional structure, especially for 5 custom hatching of poultry eggs.

Referring to the drawings:—

Fig. 1 is a view in elevation from the incubation side of an incubator embodying the invention; parts being broken away;

10 Fig. 2 is a view in elevation from the hatching side of the incubator of Fig. 1; parts being broken away;

Fig. 3 is a section on the line III—III, Fig. 1;

15 Fig. 4 is a plan view, parts being broken away;

Fig. 5 is a perspective view of a tray rack, and Fig. 6 is a detail of a modified form.

As herein disclosed the incubator housing 20 comprises end sections 1, 2, incubator side sections 3, hatching side sections 4, and top sections 5. By increasing the number of sections 3, 4, 5, the extent of the incubator between the ends 1, 2, may be as desired.

25 These sections of the incubator housing are built up as effective non-conductors of heat. The incubation side section 3 is provided with doors 6, 7, while the hatching side 4 is provided with an upper door 8.

30 Just inside the doorway of the section 3 crossbars 9 are fixed, having inwardly extending studs or heads 10 as pivot bearings, opposing similar fixed pivot bearings 11 carried by vertical partition 12 extending up-

35 ward short of the top 5 to leave opening 13 thereover between incubating chamber 14 and hatching chamber 15. Below the incubating chamber 14 is baffle 16 for dividing the air current as entering the incubating

40 chamber by way of opening 17 below the partition 12 or louver 12'. This louver or open section allows warm air to rise from the heating chamber below the fan 20 to pass into the incubating chamber, while warm air

45 as rising in the incubating chamber may pass upward through the louver 12' into the hatching chamber above the fan for recirculation down into the heating chamber for redelivery to the incubating chamber. The

50 hatching chamber 15 as herein shown is not of as great vertical height as the incubating chamber 14. The lower portion of the hatching chamber 15 extends to partition 18 having central opening 19 therein for electric fan 20 operable to accelerate air cir-

culation downward in heating chamber 21 below the hatching chamber 15.

Adjacent the end 1 is disposed oil heater 22 having heating line 23 as a riser passing into the incubator to heating pipe sections 24 60 connected by return bends 25, 26, and back by line 27 to the heater 22. In extending the heater to accommodate additional incubator sections, return bends 25 are shifted along and the space thus provided is filled in 65 with couplings 28, and unions 29, included with additional sections 24, all carried by brackets 30 from the partition 12 and disposed in the heating chamber 21 inner side below the fan 20. Controllable opening 31 70 near the floor end of the hatching side wall or section 4 permits inflow of fresh air by way of duct 32 rising to have its discharge end 33 just back of the fan 20. Above the chamber 14 of each section is foul air escape 75 opening 34 in the top sections 5. Carried by the top section 5 and mounted in the upper portion of the chamber 14 is thermostat 35 (Fig. 1) effective to operate lever 36 over the top 5, which lever 36 has link 37 downwardly extending to draft controlling disk 38 at the heater 22, thereby insuring automatic temperature control for the incubator.

Removable independent tray racks are provided. Preferably out of a medium 85 light gage of galvanized iron, side strips having bottom flanges 39 and upstanding side flanges 40 are anchored in opposing relation by middle flat brace 41 riveted to the flanges 39, and terminal strips having bottom flanges 42 are riveted to the ends of the flanges 39. From the flanges 42 depend stiffening flanges 43 centrally having bearing pivot receiving openings 44, for receiving the heads 10, 11, and thereover smaller portions 45 holding the heads against displacement. The crossbars 9, 43, may be sprung sufficiently to effect this rockable assembly of the tray racks. The side flanges 40 at the inner end carried by the bearings 11, have 90 flanges 46 extending inwardly but slightly to limit sliding movement of trays 47 into the racks. The trays 47 are drawer like as to surrounding side walls and have openwork or mesh bottoms. These trays 47 are mounted in columns in the chamber 14 and in columns in the chamber 15. The column height in the chamber 14 carries a multiple in its number of trays as to the number of trays in the vertical column in the chamber 14. This 105 110

multiple is herein shown as four in the column 15, and twelve in the column 14, so that with four trays set at a time in the column 14, such may be shifted over simultaneously to the column 15. The middle brace 41 as extending below the flanges 39, terminates in twisted ears 48, which in the vertical series on each side of the column of tray racks, are connected, as by chains 49. Any pushing of one side of a rack downward, will, through the chain from its opposite side pull the opposite side of racks therebelow upward, while on the same side will pull racks thereover downward. This means that the entire series of racks of a single column may be rocked simultaneously. This rocking of the racks serves to shift the position of eggs in the trays as to the gravity action thereon, so that the heavier yolk or chick forming portion may float differently as to the shell and not tend to settle into adhering relation with a shell side. With 100 eggs per tray and 12 trays to a column, there is thus readily effected a shifting of 1200 eggs simultaneously. As herein disclosed, two columns of incubating trays are provided for each section. For settings of every 3½ days with chicken eggs having an incubation period of 21 days, four trays of eggs per section may be set at one time, thus giving a 3½ day period for hatching by providing guides 50 at the doors 8 in the hatching chamber 15 of capacity for four trays.

In the more advanced periods of incubation less heat is required for maintaining continued growth of the chick in the egg. The period close to hatching is one during which there is actually a giving off of heat by the egg, and for live healthy chicks, such heat from the advanced stages of incubation should not build up. While the heat of hatching eggs may run close to 105° F., it is desirable to keep the temperature at least 2° or 3° lower, and with maintained circulation no ill effects may ensue to the hatching chicks. Regulation of the fresh air intake determines the rate of spill at the foul air escape, and also determines the rate of exchange or maintenance of recirculation. The extent to which recirculation may be kept up, is a factor in heat economy in the incubator operation. The egg shell is porous and the carrying on of life processes in the egg results in a demand for oxygen and a giving off of carbon dioxide. The fresh air supply is maintained normally for efficient life supporting conditions in the in-

cubator, but may be operated as a factor in assisting the temperature control, preferably only downward.

The disclosure is flexible for different capacities of operation and installation. The circulating fan 20 need be used only in such sections as are charged with eggs. The air flow is upward in the incubating chamber, and downward in the hatching chamber. The only shifting of the trays is from incubation to hatching.

The rocking of the incubating trays may be effected without opening the incubator, and all at one time. To this end from a lower one of the ears 48 of each side of a lower tray rack, actuating means, here shown as chain 51, extends upward about 75 pulley 52, fast with the top 5, thence through the incubator side 3 to horizontal shaft section 53, carried in bearings 54 on the outer side of the incubator section 3. Couplings 55 between the shaft sections permit the operation of crank 56 to effect tilting or rocking of the entire series of columns of incubating trays.

What is claimed and it is desired to secure by Letters Patent is:—

1. An incubator section embodying two columns of incubating trays, a chamber therefor open from one side of the section, a hatching chamber open from the other side of the section, superposed trays in the hatching chamber, therebelow a heating chamber, and a fan between the hatching and heating chambers.

2. An incubator embodying columns of fixed pivot bearings in pairs and a tray rack mounted in each pair of pivot bearings leaving clearway for the width of the rack over one of said bearings, said racks each being provided with detachable connecting means to a pair of said bearings permitting rack removal axially through said clearway over one of said bearings independently of the rack above or below.

3. An incubator embodying a plurality of columns of tray racks, means independently mounting the tray racks each on fixed pivots against swinging; fixed guide rollers centrally of the tray racks and flexible control means exterior of the incubator extending over said rollers to the rack columns for effecting simultaneous rocking of the racks of a plurality of columns, and trays insertable over the fixed end pivot to position on said rack.

In witness whereof I affix my signature:
HARRY E. ALMENDINGER.
